UNITED STATES PATENT OFFICE.

WILLIAM L. STEVENS, OF ORANGE, VIRGINIA.

WIRE-FENCE STRETCHER.

No. 839,332.

Specification of Letters Patent.

Patented Dec. 25, 1906.

Application filed May 5, 1906. Serial No. 315,422.

To all whom it may concern:

Be it known that I, WILLIAM L. STEVENS, a citizen of the United States, residing at Orange, in the county of Orange and State of Virginia, have invented certain new and useful Improvements in Wire-Fence Stretchers, of which the following is a specification.

This invention provides simple, easily-operable, and effective means for use in connection with the construction of wire-fencing to admit of stretching the same preliminary to fastening to the posts.

In devising means for effecting the invention due regard has been had to expediting the work and to admit of the fence-clamping means being quickly placed in position and as expeditiously removed practically at one movement of an operating-lever.

The invention consists, essentially, of a fence-clamp of novel formation, the same embodying two bars constituting clamp members, an operating-lever having pivotal connection with one end of each of the bars to effect a simultaneously relative longitudinal and lateral movement, and a wedge connection at the opposite ends of the bars formed by tapering one of said bars and providing the other bar with a keeper.

For a full description of the invention and the merits thereof, and also to acquire a knowledge of the details of construction of the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which—

Figure 1 is a perspective view of a wire-fence stretcher embodying the invention, showing the same as it will appear when in operation. Fig. 2 is a top plan view of the parts shown in Fig. 1. Fig. 3 is a front view of the clamp, parts being broken away and showing the fence gripped between the complementary members. Fig. 4 is a horizontal section on the line 4-4 of Fig. 3.

Corresponding and like parts are referred to in the following description and indicated

in all the views of the drawings by the same reference characters.

The clamp comprises two bars 1 and 2, which constitute the members between which the wire fence 3 is gripped preliminary to and during the stretching operation. The operating-lever 4 has pivotal connection with one end of each of the bars, with the result that when oscillated the bars receive a simultaneous longitudinal and lateral movement. One of the bars, as 2, has the end opposite the lever 4 tapered, as shown at 5, to coöperate with a keeper applied to the end of the bar 1, whereby the two bars are drawn together simultaneously with their longitudinal movement. The keeper fitted to the bar 1 comprises a clip 6 and a pin or bar 7, connecting the projecting ends of the side members of the clip. A roller 8 is mounted upon the pin or bar 7 to reduce the frictional contact between the tapered end 5 of bar 2 and the co-operating part 7 of the keeper. The inclination of the tapered part 5 is such with reference to the pivotal connection of the bars with the operating-lever that the two bars maintain a parallel relation throughout all stages of their movement, this being essential in order to insure a firm and uniform gripping of the fence throughout its width.

The bars 1 and 2 are preferably of tough wood, such as hickory or oak, although any material may be employed. The gripping-faces of the bars or members 1 and 2 have matching offset portions to crimp or bend the wire slightly, so as to obviate possible slipping. The offset portions may be an integral part of the bars or may consist of strips applied thereto. In the preferable construction—that is, with the bars formed of wood—metal strips 9 and 10 are attached to opposing faces of the bars, so as to pass by each other and form the offset portions which effect a crimping or bending of the wire fence. The metal strip 9 is attached to the bar 1 and is arranged to one side of a medial line, whereas the metal strip 10 is fastened to the bar 2 and arranged upon the opposite side of said medial line. By this arrangement when the bars are brought together the metal strips 9 and 10 clear each other and their inner or opposing edges form the offsets between which the wire fence is crimped, as shown

most clearly in Fig. 4. The tapered or inclined end 5 of the bar 2 is reinforced by means of a plate which sustains the wear incident to engagement with the part 7 of the keeper.

When it is required to stretch the wire fence preliminary to attaching the same to the post or like support, the clamp is applied to the fence by separating the bars 1 and 2 and passing them upon opposite sides of the fence and bringing the lower ends together and inserting the tapered part 5 behind the pin or bar 7 of the keeper, after which the operating-lever 4 is moved to cause the bars to come together and firmly grip the fence, the operating-lever being secured after the fence has been firmly gripped by means of a connection 11 and eye or like part 12. The connection 11 consists of a long hook loosely mounted upon the operating-lever 4 and adapted to have the hooked end engage with the eye 12, applied to the bar 2. The end of the connection 11, receiving the lever 4, is provided with a loop, and said connection is held in place by means of a keeper 13. After the clamp has been properly applied to the wire fencing and made secure by means of the connection 11 and coöperating part 12 suitable means are provided for coöperation with the clamp to effect tensioning of the fence by stretching the same. As shown, a grapple 14, operating-lever 15, and suitable connection are employed. The grapple 14 consists of complemental hooks which are adapted to engage with members of the clamp upon opposite sides of the fence and which hooks are connected to a short chain 16, which in turn is connected to the operating-lever 15. An anchor-chain 17 is likewise connected to the operating-lever 15 and is adapted to pass around a fence-post 18 and made secure. Preliminary to stretching the fence the operating-lever 15 is about in line with the connecting-chains 16 and 17, and upon moving said operating-lever the inner ends of the chains 16 and 17 are drawn together, and since the anchor-chain 17 is attached to a fixed part the combined movement is utilized for stretching the fence 3, as will be readily understood. After the fence has been stretched to the requisite degree the operating-lever 15 is secured by means of a short chain 19 or analogous device, thereby holding the fence under tension during the securing of the same to the fence-post, after which the operating-lever 15 is released, the stretching device removed from the clamp, and the latter loosened and disconnected

from the fence until again required for stretching another section.

Having thus described the invention, what is claimed as new is—

1. In a device of the character specified, the combination of clamp members, means for moving said members longitudinally, and means for simultaneously bringing the said members together so as to grip work placed therebetween.

2. In a device of the character specified, the combination of complemental clamp members, means for imparting a relative longitudinal movement thereto, and other means for moving the said clamp members toward each other, the same consisting of a keeper applied to one of the members and the other member having a tapered or inclined portion.

3. In a device of the character specified, the combination of clamp members, means for simultaneously moving said members longitudinally and laterally, and other means for pressing said members together, the same consisting of a keeper and a tapered or inclined end.

4. In a device of the character specified, the combination of complemental bars, an operating-lever having pivotal connection with an end of said bars to effect a simultaneous longitudinal and lateral movement thereof, and means coöperating with the opposite ends of said bars, the same consisting of a keeper and an inclined or tapered portion.

5. In a device of the character specified, clamp members each having an offset portion to effect a crimping or bending of the object gripped therebetween, and actuating means for said members.

6. In a device of the character specified, the combination of complemental bars forming clamp members, actuating means therefor, and strips applied to opposite edge portions of the gripping-faces of said bars to prevent slipping of the object clamped therebetween.

7. In a device of the character set forth, the combination of a clamp, a grapple, an operating-lever, connecting means between the operating-lever and grapple, and a post or like object, and another connection for securing the parts when drawn together.

In testimony whereof I affix my signature in presence of two witnesses.

WILLIAM L. STEVENS. [L. S.]
